UNITED STATES PATENT OFFICE.

CHARLES B. GILMORE, OF CHICAGO, ILLINOIS, ASSIGNOR TO CHICAGO FORGING & MANUFACTURING COMPANY, OF CHICAGO, ILLINOIS, A CORPORATION OF ILLINOIS.

HOOD LATCH.

Application filed August 24, 1925. Serial No. 51,907.

My invention relates to a fastening device and particularly to a device intended for use as an automobile hood latch. One object of the invention is to provide a device which will be used as a hood latch and which, while serving to hold the hood down and closed, will also force the hood inwardly against its abutment and will thus hold the hood against rattling. Another object is to provide a hood latch which operates independently of variations in position of the hood. Another object is to provide an improved finger or hand hold means for such a latch. Another object is to provide improved means for securing a spring in such a latch. Other objects will appear from time to time in the course of the specification and claims.

My invention is illustrated more or less diagrammatically in the drawings wherein—

Figure 1 is a side elevation of my latch showing it in position on the automobile;

Figure 2 is a front view of my latch, in position, and illustrating various positions which it may assume;

Figure 3 is a vertical section through my latch;

Figure 4 is a horizontal section on the lines 4—4 of Figure 3; and

Figure 5 is a side elevation of the upper part of my latch, showing a modified form; and

Figure 6 is a view similar to Figure 5 showing a still further modification.

Like parts are designated by like characters throughout the specification and drawings.

A is a portion of an automobile frame, to it may be fastened an upstanding rib or rim 40 or abutment member A¹, against which abuts the lower edge B of the hood cover when the hood is closed. Fastened to the hood B is a member B¹ terminating in a conic cam section B². Mounted above the cam B² on the locking section and herein shown as integral with it is the hook element B³ having the upwardly projecting forked members B⁴ B⁵ separated by the aperture or slot B⁵.

C is any suitable shaft or pin terminating 50 with the above member C¹ adapted to be seated in and to be contained by the socket member C² secured to the frame A. The upper end of the pin C is necked as at C³ or otherwise shaped to engage and secure any suitable washer or collar C⁴. Surrounding the

pin or shaft C is the latch cylinder D. D¹ is a spiral spring adapted to be compressed between the collar C⁴ and the lower end of the cylinder D, and thus adapted normally to thrust the cylinder D downwardly along 60 the pin C. The lower end of the spring D¹ is engaged for example by the washer D² which in turn is seated by the spring washer D³, the edges of which engage the circumferential recess D⁴ about the bottom of the 65 cylinder D.

E is a cam lug outwardly projecting from the cylinder D and adapted to engage the conic cam member B² on the hood B. E¹ is a T-shaped lug outwardly projecting from 70 the cylinder D above the cam E, the stem of the lug adapted to be slidably positioned between the hook members B⁴, the cross bar of the T being adapted to engage them to prevent outward and side swinging movement of the cylinder D.

At the upper end of the cylinder D is positioned a finger ring G from which downwardly projects the lip G¹. Referring to Figure 5 I employ instead of a single finger 80 ring G the double rings or loops G² G³ each adapted to admit a finger. Referring to Figure 6 the finger ring G is positioned to overlie the top of the cylinder D, a form desirable when maximum length of latch is 85 desired or when the latch must work in a laterally restricted space.

It will be realized that whereas I have illustrated a practical and operative device that nevertheless many changes may be made 90 in the size, shape, number, proportion and disposition of parts without departing from the spirit of my invention. I therefore wish my description and drawings to be taken as in a broad sense illustrative rather than as 95 limiting me to my specific showing.

The use and operation of my invention are as follows:

When the hood is to be released the latch handle is raised and the locking cam portion E is lifted from engagement with the cam B² and the T-shaped cam E¹ is lifted from engagement with the hooks B⁴. The whole latch may then be swung back freely in any direction, and the hood may be raised. 100 When the latch is again to be used, the hood is closed, the fore finger is passed through the ring G, the second finger engages the lower portion of the ring and the lip G¹ and the entire latch is easily lifted, the fingers 105 110

being spaced away from danger's proximity to the opposed hooks and cams. The latch is then positioned with the cam E in engagement with the opposed cam B² on the 5 hood and with the T-shaped lug E¹ lying between the hook members B⁴ on the hood. When the handle is released the cam presses upon the opposed inclined face of the cam B² and thrusts the hood both downwardly 10 and inwardly, thus at the same time holding it securely closed and preventing its rattling. The downward pressure of the spring D¹ thrusts the cam E downwardly and outwardly along the cam surface B², locks the key-shaped cam E¹ securely against the hooks B⁴, and prevents outward movement of the 15 latch away from the hood. The pressure of the spring makes it impossible for the latch to work loose and a constant downward and 20 inward thrust or pressure is insured.

The pin C, being mounted for universal movement on the frame A does not constrain the latch to any particular position, and the position of the latch is determined by the position of the cam B² and the hooks B⁴. The 25 result is a particularly flexible and adaptable latch which operates independently of changes in the relative position of the hood B and the abutment A¹, since the latch can 30 freely swing about the pivot or socket member C², to take any position, and since the spring D¹ is operative irrespective of changes in position of the latch or cam.

Referring to Figure 4 the engagement of 35 the T-shaped lug E¹ with the two members B⁴ on each side thereof prevents side swinging of the latch as a whole, that is to say, prevents its rotation about an axis positioned at the end of the T.

40 I claim:

1. In combination with an automobile, a hood, a latch member mounted adjacent said hood, means for holding said latch member against swinging movement outwardly from 45 said hood when it is in latching engagement, comprising a T-shaped lug on said latch and members on said hood adapted to engage the arms of said lug, and a cam connection between said latch and said hood 50 adapted to direct pressure both downwardly and inwardly against said hood, in response to downward movement of said latch.

2. In combination with a closure and a 55 latch for said closure, yielding means for holding said latch in engagement with said closure, a cam connection between latch and closure including an inclined faced cam outwardly projecting from said latch and opposed interconnecting members on latch and closure spaced above said cam.

3. In combination with a closure and a 60 latch for said closure, yielding means for holding said latch in engagement with said closure, a cam connection between latch and closure including an inclined faced cam out-

wardly projecting from said latch, a T-shaped member outwardly projecting from said latch and spaced above said cam, and a member on the closure adapted to engage the ends of the cross bar of said T. 70

4. In combination with a closure and a latch for said closure, yielding means for holding said latch in engagement with said closure, a cam connection between latch and closure including an inclined faced cam lug outwardly projecting from said latch, a T-shaped lug outwardly projecting from said latch and spaced above said cam lug, and a member on the closure adapted slidably to engage said T-shaped lug. 75

5. An automobile hood latch comprising a latch body, a pin along which it is slidably mounted and yielding means for thrusting it normally downwardly therealong, a cam lug and a separate locking lug vertically 80 spaced along said latch, and opposed cam and locking lugs upon the automobile hood. 85

6. An automobile hood latch comprising a latch body, a pin along which it is slidably mounted and yielding means for thrusting it normally downwardly therealong, a cam lug and a separate locking lug vertically 90 spaced along said latch, and opposed cam and locking lugs upon the automobile hood, a finger ring positioned upon said latch and 95 a finger engaging lip downwardly and outwardly projecting from the lower side thereof.

7. An automobile hood latch comprising a hollow latch body, a pin along which it 100 is slidably mounted, a spiral spring coiled about said pin, a spring abutment associated with the upper portion of said pin and a spring abutment associated with the bottom of said latch body, the latter comprising in 105 part a spring washer, the inner wall of the body being formed to receive it.

8. An automobile hood latch comprising a latch body, a spring and an abutment for said spring, comprising in part an expandable retaining member, the wall of said latch body being formed to receive it. 110

9. In combination with an automobile hood, a latch member mounted adjacent said hood, means for holding said latch member against movement away from said hood when in latching engagement, comprising a T-shaped member on said latch and members on said hood adapted to engage and receive the ends of the cross bar of said T. 115

10. In combination with an automobile hood, a latch member mounted adjacent said hood, means for holding said latch member against side swinging movement in relation to said hood when in latching engagement, comprising a T-shaped member on said latch and members on said hood adapted to engage and receive the ends of the cross bar of said T. 120

11. An automobile hood latch comprising 125

- a latch body, a latch member thereon adapted to engage the hood, yielding means normally moving said latch member in one direction, and means for lifting it in the opposite direction, comprising a finger ring positioned upon it and a finger engaging lip projecting therefrom.
12. An automobile hood latch comprising a latch body, a latch member thereon adapted to engage the hood, yielding means nor-

mally moving said latch member in one direction, and means for lifting it in the opposite direction, comprising a plurality of finger engaging elements vertically aligned along said latch member.

15

Signed at Chicago, county of Cook and State of Illinois, this 18th day of August 1925.

CHARLES B. GILMORE.
